UNITED STATES PATENT OFFICE

ELI DAVIDSON, OF CHELSEA, MASSACHUSETTS

TEMPORARY BINDER

Application filed June 5, 1925. Serial No. 35,063.

This invention relates to a temporary binder and has for one of its objects to provide an improved binder by which single leaves or groups of leaves may be detachably held in the binder in a secure manner.

Another object of the invention is to provide a temporary binder which is constructed so that the insertion or removal of any particular leaf or group of leaves may be readily accomplished without disturbing any other leaves or groups of leaves.

Other features of the invention will be more fully hereinafter set forth in the following description and the novel features of the invention will be pointed out in the appended claim.

In the drawings wherein I have illustrated some selected embodiments of my invention Fig. 1 is a perspective view showing a temporary binder made in accordance with the invention and illustrating the manner in which a group of leaves is inserted into the binder or removed therefrom;

Fig. 2 is a sectional view with a part broken out on the line 2—2, Fig. 3;

Fig. 3 is a sectional view on the line 3—3, Fig. 2;

Fig. 4 is a sectional view partly broken out on the line 4—4, Fig. 3;

Fig. 5 is a sectional view showing a different embodiment of the invention;

Fig. 6 is a fragmentary sectional view taken through the end of the back on substantially the line 6—6, Fig. 9;

Figs. 7 and 8 are views illustrating different forms of leaf-holding elements;

Fig. 9 is a perspective sectional view showing the back of the cover and illustrating the manner in which the title card may be inserted or withdrawn;

Fig. 10 is a view showing a different form of retaining member from that shown in Figs. 1 and 2.

My improved temporary binder comprises a cover member which has a back portion and front and rear cover portions, a retaining member extending longitudinally of the back and permanently secured thereto at one end, the other end of the retaining member being detachably secured to the back,

and a leaf-holding member to which the leaves or groups of leaves to be inserted in the binder may be attached which is provided with a pocket open at both ends that is adapted to receive the retaining member and through which the retaining member is inserted. The operation of inserting a leaf or group of leaves in the binder involves attaching the leaves to the holder, detaching one end of the retainer from the back and then slipping the retainer through the pocket of the holder after which the free end of the retainer is again secured to the back.

My invention is capable of being embodied in temporary binders of various sizes and in the drawings I have illustrated various constructions embodying the invention which are sufficient to indicate the wide variety of uses to which the device may be put.

Referring first to Figs. 1 to 3 the cover of the binder is indicated generally at 1 and it comprises a back member 2 and front and rear covers 3 and 4 secured thereto. The back portion of the cover may have various constructions without affecting the invention. In the device shown in Figs. 1 to 3 this back is formed with two angle iron members 5 and 6 which are held in parallel spaced relation by means of the members 7 and spacing members 8.

Each angle iron member has provision for clamping the edge of a cover member thereto, this being accomplished by means of clamping strips 9 between which and the angle iron members the edges 10 of the covers are clamped.

The spacing members 8 are in the form of sleeves through which the tie members extend, the ends of the spacing members engaging the clamping strips 9 and holding the angle irons in proper spaced relation. The tie members 7 are in the form of rods which extend through the spacing sleeves 8, each tie member having a head 11 at one end which engages the outer face of the angle iron member 6, the other end of the tie member having a screw 12 screw-threaded thereto, the head of which engages the outer face of the angle iron 5. When the screws 12 are tightened the angle iron members will

be held firmly in spaced relation and the edges 10 of the covers will be firmly clamped between the angle iron members and the clamping members 9.

5 The angle iron members 5 and 6 are so formed that their vertical legs extend beyond the horizontal legs and the extending ends of these horizontal legs are bent back on themselves as shown at 13 thereby to make 10 a better finish.

10 Associated with the back are one or more retaining members to which the leaves or groups of leaves are detachably secured. The retaining members shown in Figs. 1 and 15 2 are in the form of strips 14 of cardboard or metal or any other suitably stiff material. Each retaining member is adapted to receive a leaf-holding member indicated generally at 15. Each leaf-holding member is formed 20 with a pocket 16 extending from one end to the other thereof, which pocket is open at both ends and is of a size to receive the retaining member 14.

25 The retaining members 14 are secured to the back by means of pins or rods 17 which extend from one angle iron member to the other, each pin or rod having a head 18 which engages the outside of one of the angle iron members and having at its other end a clamping screw 19 screw-threaded therein, the head of which engages the other clamping member. These pins 17 extend through apertures 20 formed in the retaining members. Either pin can be readily removed 30 thus detachably connecting the corresponding end of the retaining member from the back by simply unscrewing the screw 19 and when the pin is thus removed then the retaining members may be swung away from the 35 back about the other pin 17. This is the condition which is illustrated in Fig. 1. When one of the pins 17 is removed the corresponding end of each retaining member 14 is detached or disconnected from the back and a 40 leaf-holding member may then be slipped onto or removed from any one of the retaining members. After the leaf-holding members have been thus applied to the retaining members the latter may be again 45 locked to the back reinserting the pins 17 through the apertures 20 of the retaining members.

50 The leaf-holding members may be constructed to hold a single leaf 21 or group of 55 such leaves. In Fig. 1 each of the two holders that are illustrated are shown as having a group of leaves secured thereto.

Figs. 7 and 8 show different types of leaf holders which may be employed. In Fig. 7 60 the leaf holder is made by taking a strip of cloth or paper and folding it back on itself and then stitching the two sides together along the line 22. This will produce the pocket 16 which extends from one end to the 65 other of the holder and will also provide two

flaps 23 between which the leaf or leaves may be secured. These flaps may be gummed or provided with adhesive as shown at 24 so that the leaves may be readily attached thereto, or may be provided with apertures 71 to 70 receive a lacing or a paper fastener or any other similar device for securing the leaves to the flaps.

75 In Fig. 8 a form of leaf holder is shown which is constructed to have a considerable number of leaves secured thereto. This holder is indicated at 15^a and it is formed by folding a strip of cloth so as to form the pocket 16 and then securing a plurality of flaps 23 to the pocket by means of stitching or 80 other suitable fastening devices 25. These flaps may be gummed as shown at 24 and may also be provided with apertures 71 so that the leaves can be fastened thereto either adhesively or by means of a lacing or other fastening device. After the strip is folded the edges may be sewed together as shown at 85 26 to form the pocket 16.

90 Each holder with the leaf or leaves attached thereto comprises a unit which may be readily placed in the binder or removed therefrom independently of any other units.

95 In some lines of business it often happens that a person is dealing with several different subjects and has several separate sheets relating to each subject. In such case it is possible to secure all the sheets relating to any one subject to a holder and then to place the different holders, each with its own group of sheets or leaves, in the binder. The 10 group of sheets or leaves relating to any one subject can then be readily removed from the binder whenever desired or may be replaced therein and this is done without any possibility that any of the separate sheets 10 belonging to any subject matter will be lost because all of such sheets or leaves are secured to the same holder.

11 I may, if desired, provide the back with a removable title card which will indicate the contents of the binder. This title card is illustrated at 27 in Fig. 9 and it is adapted to be slipped into a pocket 28 formed in the back, said pocket having the sight opening 29 through which the title on the card 27 1 may be read. The pocket 28 is open at one end as shown at 30 to permit the title card 27 to be inserted or removed.

11 In Fig. 5 I have illustrated a different embodiment of the invention wherein the back and covers of the binder are formed from one integral sheet which is folded centrally. This makes a flexible cover, the two cover portions being indicated at 31, 32 and the back portion being indicated at 33. This 1 back portion has studs 34 at each end to which the retaining members are secured, each stud having a head 35 at one end and a screw 36 removably screwed into it at the other end.

I have shown in Figs. 5 and 10 a retaining member 37 in the form of wire, such retaining member being bent at both ends to form loops 38 through which the studs 34 pass. These wire retaining members are inserted through the pockets 16 as above described and they function in the same way that the retaining members 14 do. The construction of the studs 34 is such that either stud may be removed thus disconnecting one end of the retainer from the cover thereby to permit a leaf holder to be applied thereto or removed therefrom.

I claim:

In a temporary binder, the combination with a cover having a channel-shaped back, of a pivot pin extending from one side to the other of the back at one end thereof, a plurality of retaining members pivoted on said pivot pin, said retaining members each having an aperture at its free end, a headed locking stud extending through one side of the back and to the other side, the head of the stud engaging the outer face of the first-named side and the end of the stud abutting the inner face of the other side, a screw extending through the other side and screw-threaded into the end of the stud, said stud being adapted to pass through the apertures in the retaining members thereby to detachably lock them in place, and a plurality of independent leaf-holding members each having a pocket extending from one end to the other thereof and of a size to freely receive a retaining member, each leaf-holding member having gummed flaps to which leaves may be secured and being removable from the binder independently of other leaf-holding members.

In testimony whereof, I have signed my name to this specification.

ELI DAVIDSON.
